UNITED STATES PATENT OFFICE.

HARRY NAGIN, OF PITTSBURGH, PENNSYLVANIA, ASSIGNOR TO TRI-LOK COMPANY, OF PITTSBURGH, PENNSYLVANIA, A CORPORATION OF PENNSYLVANIA.

GRATING STRUCTURE.

Application filed August 19, 1926. Serial No. 130,139

This invention relates to grating structures and is particularly useful in connection with stair treads in grating form, although it has other applications.

5 Gratings of various sorts have been employed for stair treads for a long time, but they have been open to certain objections. Regardless of whether a person is looking up or down the stairs, it is difficult in any kind 10 of light to distinguish the edge of any particular step, and in consequence accidents frequently occur. With certain types of gratings the strength of the grating is reduced, or else its expense is increased, because 15 of the necessity for specially fastening the girder bar which forms the edge of the stair tread in place.

I provide a grating having a nosing along 20 one edge thereof. This nosing may have a roughened tread face either formed directly on the nosing itself, or as a separate replaceable member. Preferably I employ a grating as described and claimed in my co-pending application, Serial No. 84,311, filed January 25 28th, 1926.

In such gratings there are employed girder bars having curved slots therein and substantially rectangular cross bars are forced into the slots. The slots are inclined in opposite 30 directions in adjacent girder bars and the step of forcing the cross bars into place causes permanent deformation of the parts thereof which engage the slots, thus locking the cross bars into place. Although it is not essential, it is desirable that the cross bars project 35 a short distance beyond the girder bars at the edge of the grating, and I therefore make these projecting end portions of the cross bars of reduced depth and utilize them for holding the nosing in place.

With a construction of this sort the steps are all clearly defined, and one great danger of accidents is thereby eliminated. I prefer, however, to corrugate the cross bars adjacent 45 the nosing and thus still further eliminate this hazard.

In the accompanying drawings which illustrate a preferred embodiment of my invention and certain modifications thereof,

50 Figure 1 is a top plan view of a portion of a stair tread grating embodying the invention;

Figure 2 is a section taken on the line II-II of Figure 1;

Figure 3 is a section taken on the line 55 III-III of Figure 2;

Figure 4 is a view to enlarged scale showing the front girder bar and a modified form of nosing in vertical section;

Figure 5 is a view corresponding to Figure 60 3, but showing a still further modified form of nosing; and

Figure 6 is a top plan view of a stairway landing showing the use of corrugated cross bars in the landing and also in the stair 65 tread.

Referring first to Figures 1 to 3, there is shown a stair tread comprising girder bars 2, having curved slots 3 formed therein. Cross bars 4 which are substantially rectangular in cross section are forced into the slots so as to permanently deform those portions of the cross bars which engage the slots and thus lock the cross bars into place. As shown in Figures 1 and 3, the slots are provided with curved bottom portions 5 which are inclined in opposite directions in adjacent girder bars, thus producing locking tongues 6 and 6^a extending in opposite directions.

The girder bar which lies at the front of the tread is indicated as 2^a. The cross bars have portions 7 which project beyond this girder bar. A nosing 8 is fitted over the projecting portions 7. The nosing comprises a vertical portion 9, a tread portion 10 and an apron 11. The portions 7 of the cross bars are preferably made of reduced depth so that the upper face of the tread portion 10 will lie flush with the top of the grating proper. This tread face may be smooth or roughened, as desired. The vertical portion 9 is provided with openings through which the portions 7 project and are riveted over as indicated at 7^a.

Figure 4 shows a construction similar to that above described except that the upper face 12 of the nosing is placed below the top of the grating and a roughened tread member 13 is fastened thereon in any desired manner. This construction is desirable in certain instances as the tread surfaces are replaceable.

Figure 5 shows a still further modified form of nosing wherein the tread surface 14 projects outwardly instead of inwardly. In both the forms shown in Figures 4 and 5, the nosings are secured to the cross bars in the same way as the nosings in Figures 1 to 3.

Figure 6 shows a stairway landing in plan. A pair of risers 15 constitute the frame work of the stairs and to these risers are secured stair treads indicated generally by the reference character 16. A landing, indicated by the reference character 17, is also shown. In both the landing and the stair treads, nosings 18, girder bars 19 and cross bars 20 are provided. It will be noted that the cross bars 20 are generally straight, but that near the edge of the stair treads, or of the landing, as the case may be, they are corrugated. A corrugated grating is more fully disclosed and claimed in my co-pending application Serial No. 130,140, filed August 19, 1926. This corrugated construction more clearly indicates the edge of a tread and is, therefore, of value in preventing accidents.

I have illustrated and described a preferred embodiment of the invention but it will be understood that it is not thus limited, since it may be otherwise embodied within the scope of the following claims.

I claim:

- 25 1. A grating having a nosing along one edge thereof, the nosing having a separate roughened tread member whose top surface is substantially flush with the tread surface of the grating.
- 30 2. A grating having a nosing along one edge thereof, the nosing having a separate removable tread member whose top surface is substantially flush with the tread surface of the grating.
- 35 3. A grating comprising a plurality of girder bars and cross bars extending across the several girder bars, the cross bars projecting beyond a girder bar at one side of the grating and a nosing running alongside said girder bar and secured to the cross bars.
- 40 4. A grating comprising a plurality of girder bars and cross bars extending across the several girder bars, the cross bars projecting beyond a girder bar at one side of the grating and a nosing running alongside said girder bar and secured to the cross bars, the cross bars being corrugated adjacent the nosing.
- 45 5. A grating comprising girder bars and cross bars secured thereto, the cross bars projecting beyond a girder bar at one side of the

grating, a nosing lying alongside the girder bar and secured to the projecting portions of the cross bars, such projecting portions being of reduced section so as to leave the top of the nosing flush with the top of the grating.

6. A grating comprising a plurality of girder bars and cross bars extending in substantially straight lines across a portion of the grating, the cross bars being corrugated adjacent an edge of the grating, and a nosing alongside said edge portion.

7. A grating comprising a plurality of girder bars and cross bars extending across the several girder bars, the cross bars extending in substantially straight lines over a portion of the grating, but being corrugated adjacent an edge thereof.

8. A grating, comprising a plurality of notched girder bars and cross bars lying in the notches and extending through a plurality of the girder bars, the cross bars projecting beyond a girder bar at one edge of the grating, and a nosing secured to the projecting cross bar portions.

9. A grating, comprising a plurality of notched girder bars and cross bars lying in the notches and extending through a plurality of the girder bars, the cross bars projecting beyond a girder bar at one edge of the grating, and a nosing secured to the projecting cross bar portions, the top of the nosing being on substantially the same level as the top of the girder bars.

10. A grating, comprising a plurality of girder bars and cross bars extending over the several girder bars and secured to the several girder bars, the cross bars projecting beyond a girder bar at one side of the grating, and a nosing secured to the cross bars.

11. A grating comprising a plurality of girder bars, cross bars extending over the several girder bars and projecting beyond a girder bar at one edge of the grating, and a nosing secured to the projecting portions of the cross bars, the cross bars being secured to a girder bar remote from the nosing.

In testimony whereof I have hereunto set my hand.

HARRY NAGIN.
